Horoway and Horoway

UNITED STATES PATENT OFFICE

OTTO HAENTJENS, OF HAZLETON, PENNSYLVANIA

MULTISTAGE CENTRIFUGAL PUMP

Application filed January 17, 1929. Serial No. 338,179.

This invention relates to multi-stage centrifugal pumps which are provided with means for priming the centrifugals, and the main object of this invention is to provide means whereby the connection to the priming pump may be cut off with certainty when the centrifugal has been primed.

In the accompanying drawings:

Fig. 1 is a somewhat diagrammatic illustration of a pumping system in which my invention is embodied;

Fig. 2 is a sectional view drawn to a larger scale illustrating a part of the multi-stage centrifugal pump and the priming check valve provided with my present invention.

For purposes of illustration I have shown in Fig. 1 a general layout of a centrifugal pumping system which embodies the principal features of the system of my Patent 1,513,705, dated October 28, 1924. The centrifugal is shown as a three stage pump at 5, 5' and 5², to be driven by a motor 18, the suction being indicated at 16 and the discharge at 17. I have shown at 19 the priming pump connected by piping 21 and 22 through a priming check valve 6 to the first stage of the centrifugal. There is in addition in this piping connection a vacuum breaker 24 such as disclosed in my above mentioned patent, and there is also a drainage pipe 62 with a drainage check valve at 63 also such as disclosed in the mentioned patent.

The detailed construction of the priming check valve may be in part substantially the same as that disclosed and claimed in my Patent 1,481,199 dated January 15, 1924. The movable part of this priming check valve 10 in the casing 6 is mounted on a stem 13 which finds its bearings in the opposite ends of the casing of the valve. This valve has lateral openings 12 into the valve chamber and when moved fully to the left finds a seat at 24 to close off the connection to the priming pump through the passage S and pipe 22. The other side of the valve 10 is in communication through the passage 7 with the first stage of the centrifugal.

This valve 10 is normally held open, to the right, by a spring or electro-magnetic means.

In the drawing I have indicated a solenoid 28 and solenoid core which latter is carried by the stem of the valve as described in my Patent 1,481,199. The operation of the valve thus far will be sufficiently obvious and is 55 fully described in my mentioned patent.

When such a priming check valve is employed in connection with a multi-stage centrifugal pump it has been found that sometimes there is not sufficient pressure in the first stage of the centrifugal to close this priming check valve 10 when the centrifugal has been primed. My present improvement consists in providing means whereby the priming valve shall be closed with certainty 65 at the desired time. For this purpose I extend the stem of the valve 10 to the right and mount thereon a piston 40 working in a chamber 41 closed by a cap 43. Then I provide a communication 44 between the second stage 70 of the centrifugal and the space in the chamber 41 on the right hand side of this piston 40. With this construction I find that the pressure from the second stage on this piston when the centrifugal has been primed and 75 started will be sufficient to insure the closing of the valve 10 to its seat 24 and thus shut off the connection with the priming pump at the desired time.

I claim as my invention:

1. A series multi-stage centrifugal pump in combination with a priming pump connected to the discharge side of the first stage of said centrifugal pump, a priming check valve between the two pumps and subjected 85 to the discharge pressure of said first stage in a direction to close said check valve and means controlled by one of the centrifugal stages other than the first to aid in closing said priming check valve when the centrifugal has been primed and started.

2. A series multi-stage centrifugal pump in combination with a priming pump connected to the discharge side of the first stage of said centrifugal pump, a priming check 95 valve in said connection and subjected to the discharge pressure of said first stage in a direction to close said check valve, a piston operatively connected to said priming check valve and a connection whereby the pressure 100

in the second stage of the centrifugal pump may act upon said piston in a direction to close the priming check valve when the centrifugal has been primed and started.

5 In testimony whereof I have signed my name to this specification.

OTTO HAENTJENS.
